UNITED STATES PATENT OFFICE.

KARL LÜSKE, OF BUDAPEST, AND ANDOR MOUSSONG AND PAUL MOUSSONG, OF TOLNA-HOGYESZ, HUNGARY.

STOVE.

Application filed August 29, 1921. Serial No. 496,671.

To all whom it may concern:

Be it known that we, KARL LÜSKE and ANDOR MOUSSONG and PAUL MOUSSONG, citizens of Hungary, residing at Budapest and 5 Tolna-Hogyesz, respectively, have invented certain new and useful Improvements in Stoves (for which we have filed an application in Hungary August 2, 1920), of which the following is a specification.

10 Our invention relates to stoves and more especially to stoves of the down-draft type.

One object of our invention is to provide a stove capable of affecting perfect combustion of the fuel.

15 Another object is to provide a stove in which coals of poor quality and containing large percentages of ash may be used.

Other objects will be partly obvious and partly pointed out hereinafter.

20 In the accompanying drawing an embodiment of our invention is illustrated by way of example.

Fig. 1 is a sectional elevation of the stove.

Fig. 2 is a sectional elevation on a plane 25 at a right angle with the sectional plane of Fig. 1.

Fig. 3 is a perspective view of the stove.

Fig. 4 is a sectional elevation on a larger scale of the means for supplying combustion 30 air.

Fig. 5 is a perspective view of the grate at the bottom of the fuel shaft.

Fig. 6 is a perspective view of the vertical grate.

35 Referring to Figs. 1 and 2, *l* is a casing provided at the top or at the side wall with a door *d* for charging the fuel, and forming as airtight a closure as possible. *b* is a grate dividing the casing *l* into a larger

40 upper part forming the fuel shaft and a smaller lower part *g* forming the ash pit.

—*i*— is the exit flue communicating by means of the substantially vertical flues *h*, *h* and by means of openings *m* with the ash 45 pit *g*. *f* is a tightly closing door for removing the ash from the pit. —*r*— is a nozzle for the admission of the combustion air immediately above the grate *b* at the bottom of the fuel shaft provided with means, as the 50 rotary valve *r'*, for regulating the air admission. As shown in the drawing, the nozzle *r* is preferably arranged on a door *e* on the side wall of the casing *l*, which door consists most preferably of two parts 55 *e*, *e'*. The lower part *e* of the door can be

opened for inspection without admitting too much air, while both parts *e*, *e'* can be opened for the purpose of kindling the fire. *k* is a vertical grate located behind the door *e*, *e'* with faces inclined towards the grate *b* and provided preferably with openings *k'*. *j* is an apertured fire pot receiving the fuel and serving at the same time as means to keep the part of the grate *b* adjacent to the discharge end of the nozzle *r* free of coal and ashes. Hence the combustion air entering the fuel shaft at its bottom through the nozzle *r* will be divided, one part of the air draft being directed through the brazier at the bottom of the fuel column contained in the apertured fire pot *j* causing the gasification of the fuel, while the other part of the air will pass directly through the openings *b'* of the grate without coming in touch with the fuel, will become heated by passing the hot grate and will be directed towards the flames formed underneath the grate and will complete the combustion of the gases on the outer surface of the flames. If no apertured fire pot *j* is used, other means must be provided to keep free of coal the part of the grate adjacent to the nozzle *r*, for example, by means of the vertical grate *k* which in this case must be placed over the part of the grate *b* to be kept free of coal.

As will be seen from the drawing, it is most preferable to arrange the openings *m* of the ash pit communicating with the flues *h*, *h* on two opposite sides of the grate *b* and the discharge end of the air-nozzle *r* on the third side of the grate, whereby the complete combustion of the inverted flames is absolutely granted.

We claim as our invention and desire to secure by Letters Patent:—

1. In a down-draft stove, the combination of a substantially air-tight casing, an apertured fire pot, grate and ash-pit, an exit flue communicating with the said ash-pit, means to admit air to the bottom of the fuel shaft and means to keep free of fuel a part of the grate adjacent to the discharge end of the air admission, permitting part of the air to flow directly through the said free part of the grate and part of the air to pass through the fuel before reaching the grate, said free part of the grate being provided with openings for the passage of the air.

2. In a down-draft stove, the combination

of a substantially air-tight casing, an apertured fire pot, grate and ash-pit, an exit flue communicating on two opposite sides of the grate with the said ash-pit, means to admit 5 on the third side at right angles to the former two sides of the grate air to the bottom of the fuel shaft and means to keep free of fuel a part of the grate adjacent to the discharge end of the air admission, permitting 10 part of the air to flow directly through the said free part of the grate and part of the air to pass through the fuel before reaching the grate, said free part of the grate being provided with openings for the passage of the air.

3. In a down-draft stove, the combination of a substantially air-tight casing, an apertured fire pot, grate and ash-pit, an exit flue 20 communicating with the said ash-pit, a door in the said casing adjacent to the bottom of the fuel-shaft, a nozzle in said door communicating with the atmosphere and having its discharge end located over one edge of the said grate and means to keep free of fuel 25 a part of the grate adjacent to the discharge end of the said nozzle, permitting part of the air to flow directly through the said free part of the grate and part of the air to pass through the fuel before reaching the grate, 30 said free part of the grate being provided with openings for the passage of the air.

4. In a down-draft stove, the combination of a substantially air-tight casing, an apertured fire pot, grate and ash-pit, an exit flue 35 communicating on two opposite sides of the grate with the said ash-pit, a door in the said casing adjacent to the bottom of the fuel-shaft, a nozzle in said door communicating

with the atmosphere and having its discharge end located over one edge of the said 40 grate and means to keep free of fuel a part of the grate adjacent to the discharge end of the said nozzle, permitting part of the air to flow directly through the said free 45 part of the grate and part of the air to pass through the fuel before reaching the grate, said free part of the grate being provided with openings for the passage of the air.

5. In a down-draft stove, the combination of a substantially air-tight casing, an apertured fire pot, grate and ash-pit, an exit flue 50 communicating on two opposite sides of the grate with the said ash-pit, a door in the said casing adjacent to the bottom of the fuel-shaft, a nozzle in said door communicating 55 with the atmosphere and having its discharge end located over one edge of the said grate, means to regulate the air admission through the said nozzle and a substantially vertical grid to keep free of fuel a part of the 60 grate adjacent to the discharge end of the said nozzle, permitting part of the air to flow directly through the said free part of the grate and part of the air to pass through the fuel before reaching the grate, 65 said free part of the grate being provided with openings for the passage of the air.

In testimony whereof we affix our signatures.
